UNITED STATES PATENT OFFICE.

STUART W. CRAMER AND WILLIAM B. HODGE, OF CHARLOTTE, NORTH CAROLINA;
SAID HODGE ASSIGNOR TO SAID CRAMER.

SPRAY-NOZZLE FOR HUMIDIFIERS.

1,028,813.

Specification of Letters Patent.

Patented June 4, 1912.

Original application filed October 26, 1910, Serial No. 589,199. Divided and this application filed January 26, 1912. Serial No. 673,674.

To all whom it may concern:

Be it known that we, STUART W. CRAMER and WILLIAM B. HODGE, citizens of the United States, residing at Charlotte, in the county of Mecklenburg and State of North Carolina, have invented certain new and useful Improvements in Spray-Nozzles for Humidifiers; and I do hereby declare the following to be a full, clear, and exact description of the invention, such as will enable others skilled in the art to which it appertains to make and use the same.

The present application for a patent is a division of our application #589,199, filed October 26th, 1910.

Our invention relates primarily to humidifiers for moistening the air in mills, factories and other buildings and has especial reference to water spray-nozzles.

20 The particular form of spray-nozzle to which our invention refers, and to which it is applicable, is that consisting of a body member arranged for attaching to a supply pipe, a jet discharge orifice either incorporated directly into the body part or into a 25 detachable member adjustably secured thereto, and a pillar upon which is supported a jet breaking up pin, opposite to and concentrically arranged with reference to the discharge orifice.

30 The object of the invention is to secure great accuracy in centering the orifice in line with its breaking up pin, as well as increasing the durability of the device, and 35 the invention consists in certain improvements, which will be fully disclosed in the following specification and claims.

In the accompanying drawings, which form part of this specification:—Figure 1 40 represents a sectional view of the nozzle with the pin and bushing as they appear in the casting, and Fig. 2 is a like view of a completed nozzle ready for use.

Reference being had to the drawings and 45 the designating characters thereon, the numeral 1 indicates the nozzle-frame or yoke, cast of suitable metal as part of the body 6. The frame or yoke supports the pillar 5 in which is inserted a pin 4, of material harder 50 than the body or yoke opposite and directly under the orifice 7, through which water is discharged. The body is provided with a screw-thread 2, by which it is attached to a

pipe, not shown, for conveying water to be sprayed.

55 In constructing nozzles heretofore, it has been the common practice to attempt to get the pin 4, Fig. 2, opposite the opening or orifice 7 by mere mechanical methods. Owing to the fact that the accurate centering of this pin exactly opposite and in alignment with the orifice almost solely determines the efficiency of the nozzle, that is, the ability to divide the water used in extremely fine spray, numerous methods have 60 been used to get this centering perfect. Inasmuch as the diameter of the pin 4 is usually slightly greater than that of the orifice 7 through the bushing or nipple 3, the proper and permanent mechanical centering 65 of the pin with the orifice is extremely difficult. If these are cast in, the inability to hold the pin 4, Fig. 2, perfectly rigid during the contraction of the metal renders it 70 likely to spring one way or the other, and when the casting is finally cool it is not 75 axial with the nozzle orifice.

80 In previous types of nozzles, the orifices have been in the metal of the casting itself. In other words, a hole drilled through the casting to form the orifice at the proper point opposite the pin. An objectionable feature of this construction is that the water 85 passing through at high velocity wire draws the sides of the orifice, this is on account of the fact that the metal used in casting is not uniformly hard and homogeneous. To 90 overcome this grooving action, and to aid in centering the pin, we have arranged the bushing 3, Fig. 1 of less erosive material 90 than the body, in connection with the pin 4 to be held each by the other in their respective positions, and the metal of the nozzle body cast around them while they are thus held rigidly. The bushing and the pin become 95 homogeneous with the body and both are permanently embedded therein. It is advisable to have the pin 4 as shown in Fig. 2 slightly larger in diameter than the orifice of the bushing 3. On this account the pin 4 100 is made with two diameters, the smaller diameter exactly the same as the inside diameter of the orifice in the bushing, whereas the larger diameter of the pin 4 is of the proper size to break up the stream of water to the 105 best advantage.

The bushing or nipple 3 is slipped on the smaller end of the pin 4 with a tight fit, as shown in Fig. 1, which holds it axially central with the pin. The casting is then made and finally the end of the pin which extends from the lower end of the bushing is filed off, leaving the proper space between the lower end of the bushing and the upper end of the pin to get the desired water breaking effect. Owing to the fact that the pin and the bushing have been held axially while the molten metal was poured around them and allowed to cool, it can be readily seen that these two parts are exactly in line with each other, and after filing off the end of the pin and removing the part in the orifice, the stream of water issuing from the orifice of the bushing 3 will strike the upper end of the pin 4 exactly central and result in a uniform spray of water surrounding pin 4.

It is, of course possible to use pins and bushings of any desired material so as to resist corrosion and wear and of any desired ratio between the diameter of the orifice and the diameter of the pin.

Having thus fully described our invention, what we claim is—

1. A spray nozzle comprising a body and a frame and having a discharge orifice whose walls are of material different from the body and integrally united therewith, and a pin integrally united to the body in alinement with said orifice and forming the breaking surface of the nozzle.

2. A spray nozzle comprising a body and a frame and having a discharge orifice whose walls are of less erosive material than the body and integrally united therewith, and a pin integrally united to the body in alinement with said orifice and forming the breaking surface of the nozzle.

3. A spray nozzle comprising a body and a frame and having a discharge orifice whose walls are of material different from the body and integrally united therewith, and a pin of greater diameter than said orifice, integrally united to the body in alinement with the orifice and forming the breaking surface of the nozzle.

4. A spray nozzle comprising a body and a frame and having a discharge orifice whose walls are of harder material than the body and integrally united therewith, and a pin of harder material than the body, integrally united thereto in alinement with said orifice and forming the breaking surface of the nozzle.

In testimony whereof we affix our signatures, in presence of two witnesses.

STUART W. CRAMER.
WILLIAM B. HODGE.
